POWER TRANSMISSION

Ferris T. Harrington, Detroit, and Ralph L. Tweedale, Birmingham, Mich., assignors to Vickers Incorporated, Detroit, Mich., a corporation of Michigan

Application May 17, 1947, Serial No. 748,752

5 Claims. (CL. 60—52)

1

This invention relates to power transmissions, particularly to those of the type comprising two or more fluid pressure energy translating devices, one of which may function as a pump and another as a fluid motor.

The invention is more particularly concerned with a power transmission system of the type disclosed in the patent to Herman, No. 2,274,603. The transmission therein disclosed is comprised of a pressure fluid source, a reversible fluid motor for operating a load device, and a control panel containing the necessary valving for producing a rapid advance, coarse feed, fine feed, rapid reverse, and stop operation of the load. The valving contained in the panel is comprised of a control valve and flow control mechanism, the latter of which consists of a coarse feed throttle, a fine feed throttle, and a pressure compensating valve. The compensating valve is of the well known type which is responsive to the pressure drop across the throttle for maintaining a constantly regulated flow of fluid through the throttle. The compensating valve assumes numerous regulating positions in response to the pressure drop across the throttle for regulating the flow through the latter. However, when fluid flow ceases through the compensating valve, it is biased to a non-regulating, fully open position. The control valve is shiftable to one position for connecting the coarse feed throttle and compensating valve to the exhaust end of the motor for producing a coarse feed movement of the motor. The control valve is also shiftable to another position for connecting the throttles in series and the compensating valve to the exhaust end of the motor for producing a fine feed movement of the motor. When the control valve is shifted to the motor stop position, fluid flow through the flow regulating valve mechanism is interrupted.

In the past, some difficulty has been experienced when the load device is started into a feeding position from rest. This difficulty lies in the inability of the compensating valve to immediately assume a normal regulating position. During the time interval that this requires, fluid is exhausted from the motor at a greater than normal rate causing the slide to jump ahead at the beginning of a feed movement. This is particularly objectionable in machine tools where, for some reason, it may be necessary to stop the slide during the middle of a cut and then if the feeding movement be resumed, the slide jumps ahead momentarily causing breaking of the cutting tool.

It is therefore an object of this invention to

2

provide an improved control panel which overcomes this difficulty.

It is a further object of this invention to provide in a panel of this type a back pressure valve for inducing a flow of pressure fluid through the flow regulating valve mechanism when the motor is stopped. In this manner, if the motor is restarted in a feed movement after interruption thereof, the compensating valve will already be in a flow regulating position and motor jump will be prevented.

Further objects and advantages of the present invention will be apparent from the following description, reference being had to the accompanying drawings wherein a preferred form of the present invention is clearly shown.

In the drawings:

Figure 1 is a circuit diagram and cross section of a control panel embodying a preferred form of the present invention and showing the passageways in the same plane for purposes of illustration.

Figure 2 is a view corresponding to that of Figure 1, but showing the control valve in the panel shifted to another position.

Figure 3 is a view corresponding to that of Figure 1 but showing the control valve therein shifted to still another position.

Figure 4 is a view corresponding to that of Figure 1, but showing the control valve therein shifted to still another position.

Referring now to Figure 1, there is shown a pump 10 which may be driven by an electric motor 12 and which is connected to a tank 14 by means of a suction conduit 16. A pressure fluid delivery conduit 18 is connected to the pump 10 and to a pressure inlet port 20 of a control panel 22. The panel 22 is also provided with a tank port 24 which is connected to the tank 14 by means of a conduit 26 and with motor ports 28 and 30 which are connected to opposite ends of a fluid motor 32 by means of conduits 34 and 36. The motor 32 is of the reciprocating type having a piston 38 connected to which is a piston rod 40 which extends through the motor. The motor 32 may be connected in the conventional manner to a reciprocating work table of a machine tool (not shown) for the purpose of driving the same.

A control valve 42 is shiftable mounted in a bore 44 of the panel 22. The control valve 42 is provided with a centrally located land 46, lands 48 and 50 on either side of land 46, and extreme end lands 52 and 54. The lands control ports spaced along the bore 44 including a pressure port 56, motor ports 58 and 60 located on opposite sides

of port 56, extreme opposite end tank ports 62 and 64, and throttle ports 66 and 68. The external pressure, tank, and motor ports 20, 24, 28, and 30 are respectively separately connected to their corresponding valve bore ports by means of conduits 70, 72, 74, and 76. A branch conduit 78 of the motor conduit 76 is connected to an inlet chamber 79 and an outlet chamber 80 of a pressure compensating valve 82, to a bore 84 within which is mounted a coarse feed throttle 86, to the throttle port 66, and to a bore 88 within which is mounted a fine feed throttle 90. The fine feed throttle bore 88 is connected to the valve bore throttle port 64 by means of a conduit 92. The tank port 62 is connected to the tank conduit 72 by means of a conduit 94.

Mounted within the conduit 94 is a back pressure valve 96. A drain conduit 98 connects the lower end of the valve bore 44 to the tank conduit 72 while a drain conduit 100 connects the upper end of the bore 44 to the tank port 24. The compensating valve 82 is comprised of a piston 102 connected to which is a stem 104 having an upper land 106 and a tapered lower land forming a valve 108 which controls fluid flow between the inlet chamber 79 and the outlet chamber 80. A spring 110 of predetermined resistance located in an upper chamber 112 of the compensating valve 82 in abutting relationship with the piston 102 biases the valve 108 to the fully open position. The compensating valve 82 is adapted to be responsive to the pressure ahead of the throttles 86 and 90 by means of a conduit 114 which connects the outlet chamber 80 to a pressure chamber 116 below the piston 102. The compensating valve 82 is adapted to be responsive to the pressure beyond the throttles 86 and 90 by means of a branch conduit 118 of the drain conduit 100 which is connected to the upper chamber 112. The valve 42 is adapted to be shifted by means of a ball-ended rod 120 connected to the lower end of the valve 42, the former of which is connected to a rotatable shaft 122. The shaft 122 is adapted to be rotated during the movement of the member being reciprocated at various stages of the cycle of the movement in the conventional manner. Incorporated in the pump delivery conduit 18 is a relief valve 124 of suitable construction which is adapted to exhaust to the tank 14, excessive pressure fluid by means of a conduit 126.

Referring now to Figure 1, in operation, with the valve 42 shifted to the position shown in Figure 1, a rapid advance movement of the motor 32 will take place. Pressure fluid entering the pressure port 20 is conducted to the external motor port 28 by means of conduit 70, valve bore ports 56 and 58, and conduit 74, and to the head end of the motor 32 by means of conduit 34. Fluid is free to discharge from the rod end of the motor 32 to the tank 14 by means of conduit 36, motor port 30, conduit 76, valve bore ports 60, 66, 68, and 64, conduit 72, tank port 24, and conduit 26.

Referring now to Figure 2, if the valve 42 is shifted during the rapid advance movement of the motor to the position shown in Figure 2, a coarse feed movement of the motor will take place. Pressure fluid from the pump 10 is delivered to the head end of the motor 32 in the same manner as described in the rapid advance movement. However, discharging fluid from the rod end of the motor 32 must flow to the tank through the compensating valve 82 and coarse feed throttle 86. The land 46 blocks the valve bore motor port 60 and fluid entering the motor

port 30 must flow to the tank 14 by means of conduits 76 and 78, compensating valve 82, coarse feed throttle 86, valve bore ports 66, 68, and 64, conduit 72, tank port 24, and conduit 26. Although the conduit 78 is also open to fine feed throttle 90, the fluid will take the course of at least resistance and flow to the tank 14 rather than through the fine feed throttle 90. The compensating valve 82 will function in the well known manner to maintain the pressure drop across the throttle 86 constant and thereby maintain a uniform flow through the throttle. The resistance of the spring 110 determines the pressure drop across the throttle. Any increase of pressure ahead of the throttle 86 in conduit 78 is immediately present in chamber 116 to shift the piston 102 upwardly and thus the valve 108 towards the closed position to restrict the flow of fluid from the inlet chamber 79 to the outlet chamber 80. A decrease of pressure in conduit 78 ahead of the throttle 86 results in an immediate decrease of pressure in the lower chamber 116 and the spring 110 will shift the piston 102 downwardly resulting in the valve 108 moving towards the open position to permit more flow fluid from the inlet chamber 79 to the outlet chamber 80. The valve 108 will assume numerous regulating positions between the fully open and fully closed positions for maintaining the pressure drop across the throttle uniformly constant.

It should be noted that if fluid flow is interrupted to the compensating valve and throttle that the spring 110 will bias valve 108 to the fully open position or a non-regulating position.

If the valve 42 is shifted slightly downward from the position shown in Figure 2, a fine feed movement of the motor 32 will take place. Fluid is continued to be directed to the head end of the motor, the same as in the rapid advance and coarse feed cycles of the motor. Fluid discharging from the motor must also flow through the compensating valve 82 and the coarse feed throttle 86 as in the coarse feed cycle of the motor. However, the land 50 will now block the conduit 78 from the port 68 and fluid must flow from the coarse feed throttle 86 through the fine feed throttle 90, as shown by dotted arrows, and thence to the tank 14 by means of conduit 92, valve ports 68 and 64, conduit 72, external tank port 24, and conduit 26. Due to the fact that throttle 90 and throttle 86 are now connected in series, and, because throttle 90 produces a greater restriction than throttle 86, the latter throttle will not be effective. The compensating valve 82 will maintain a constant pressure drop across the throttle 90 in the same manner as the throttle 86 in the coarse feed movement. Consequently, the flow across the throttle 90 will be uniformly regulated at the rate desired.

Referring now to Figure 3, if the valve 42 is shifted to the position shown, the motor 32 will be stopped. The pressure port 20 is directly connected to the tank port 24 by means of conduit 70, valve ports 56, 58, and 62, conduit 94, back pressure valve 96, and conduit 72. However, the back pressure valve 96 is adapted to have sufficient resistance to divert a portion of the pump flow through the compensating valve 82 and the throttles 86 and 90. The resistance created by the back pressure valve 96 will direct a portion of pump flow through valve ports 56 and 60, conduits 76 and 78, compensating valve 82 and throttle 86, valve port 66, throttle 90, conduit 92, valve ports 68 and 64, and conduit 72 to the tank port 24. The resistance of the back

pressure valve 86 will be set to divert a portion of this pump flow through the flow regulating valve mechanism without causing excessive heating within the system.

Referring now to Figure 4, if the valve 42 is shifted to the position shown in Figure 4, a rapid return movement of the motor will take place. Fluid from the pump 10 entering pressure port 20 is conducted to motor port 30 by means of conduit 10, valve ports 56 and 60, and conduit 78, and thence to the rod end of the motor 32 by means of conduit 36. Fluid from the head end of the motor 32 is discharged to the tank 14 by means of conduit 34, motor port 28, conduit 74, valve ports 58 and 62, conduit 94, back pressure valve 96, conduit 72, tank port 24, and conduit 26.

It should be noted that the valve 108 is prevented from moving to the fully open position by this procedure and will be maintained in a normal regulating position while the motor is stopped. Consequently, if during a coarse feed or fine feed movement of the motor, the motor is stopped and then the feed movement is resumed, the compensating valve 82 will be in a normal regulating position to maintain the flow across either or both throttles uniformly constant. If the back pressure valve 96 was not incorporated in the panel 22, the valve 108 would be biased to a fully open position, or a non-regulating position, when the motor 32 was in a stopped position. The full pump delivery would be free to flow to the tank 14, and fluid flow through the flow regulating valve mechanism would be interrupted, thereby permitting the valve 108 to open to the fully open position.

Thus, if the motor 32 were stopped during a feed movement, and then the feed movement resumed, the compensating valve 82 would not be able to immediately assume a regulating position. During this time lapse, a flow of fluid from the inlet chamber 79 to the outlet chamber 80 would result in excess of which is the normally regulated amount. This slight but excessive amount of fluid above the normal regulated amount causes the motor to jump and is the cause of ruining cutting tools.

Thus, by incorporating the back pressure valve in the panel in the manner described, the compensating valve 82 is maintained in a normal regulating position when the motor is stopped, and in particular, while stopped during a feed movement and is already in a position to maintain a regulated flow of fluid through the throttle when the motor is restarted in the feed movement.

While the form of embodiment of the invention as herein disclosed constitutes a preferred form, it is to be understood that other forms might be adopted, all coming within the scope of the claims which follow.

What is claimed is as follows:

1. A unitary control panel for use in a hydraulic power transmission having a fluid pump and reversible fluid motor comprising in combination a valve block having external connection ports, a control valve connected to said ports and shiftable to a plurality of positions for controlling the motor including motor advance, feed, reverse, and stop positions, flow control mechanism for producing a feed movement of the motor including a compensating valve of the type which opens fully whenever the fluid flow through the compensating valve is interrupted, and means for inducing a flow of pressure fluid through the compensating valve when

the control valve is shifted to the stop position thereby operating the compensating valve to a throttling position ready to immediately control the feed movement of the motor when the control valve is shifted from the stop to the feed position.

2. A unitary control panel for use in a hydraulic power transmission having a fluid pump and reversible fluid motor comprising in combination a valve block having external connection ports, a control valve connected to said ports and shiftable to a plurality of positions for controlling the motor including motor advance, feed, reverse, and stop positions, flow control mechanism for producing a feed movement of the motor including a compensating valve of the type which opens fully whenever the fluid flow through the compensating valve is interrupted, and a back pressure valve for inducing a flow of pressure fluid through the compensating valve when the control valve is shifted to the stop position thereby operating the compensating valve to a throttling position ready to immediately control the feed movement of the motor when the control valve is shifted from the stop to the feed position.

3. A unitary control panel for use in a hydraulic power transmission having a fluid pump and reversible fluid motor comprising in combination a valve block having external connection ports, flow control mechanism for producing two different feed rates including a coarse feed throttle and a fine throttle through which fluid is adapted to flow at a controlled rate and an automatic pressure compensating valve responsive to the pressure drop across the throttles for maintaining the flow rate through the throttles uniformly constant, said compensating valve being of the type which opens fully whenever the fluid flow through the compensating valve is interrupted, a control valve connected to said ports and to the flow control mechanism shiftable to a plurality of positions for controlling the motor operation including motor advance, coarse feed, fine feed, reverse, and stop operations thereof, and means for inducing a flow of pressure fluid through the compensating valve when the control valve is shifted to the stop position thereby operating the compensating valve to a throttling position ready to immediately control the movement of the motor when the control valve is shifted from the stop position to either of the feed positions.

4. A unitary control panel for use in a hydraulic power transmission having a fluid pump and reversible fluid motor comprising in combination a valve block having external connection ports, flow control mechanism for producing two different feed rates including a coarse feed throttle and a fine throttle through which fluid is adapted to flow at a controlled rate and an automatic pressure compensating valve responsive to the pressure drop across the throttles for maintaining the flow rate through the throttles uniformly constant, said compensating valve being of the type which opens fully whenever the fluid flow through the compensating valve is interrupted, a control valve connected to said ports and to the flow control mechanism shiftable to a plurality of positions for controlling the motor operation including motor advance, coarse feed, fine feed, reverse, and stop operations thereof, and a back pressure valve for inducing a flow of pressure fluid through the compensating valve when the control valve is

shifted to the stop position thereby operating the compensating valve to a throttling position ready to immediately control the movement of the motor when the control valve is shifted from the stop position to either of the feed positions.

5. In a hydraulic power transmission the combination of a fluid source, a fluid pump, a reversible fluid motor, flow control mechanism for regulating the speed of the motor comprising a coarse feed throttle and a fine feed throttle through which fluid is adapted to flow at a regulated rate and an automatic pressure compensating valve responsive to the pressure drop across the throttles for maintaining the regulated rate, said compensating valve being of the type which opens fully whenever the flow through the compensating valve is interrupted, a back pressure valve and a control valve shiftable to a first and a second position for alternately connecting opposite ends of the motor to the source and the pump and by-passing the flow control mechanism for causing rapid advance and rapid reverse movements of the motor, to a third position for connecting one end of the motor to the pump and the opposite end of the motor to the compensating valve, to the coarse feed throttle and to the source for producing a coarse feed movement of the motor to a fourth position for connecting the pump to one end of the motor

and the opposite end to the throttles in series and the compensating valve for producing a fine feed movement of the motor and to a fifth position for connecting the pump to the back pressure valve, to the compensating valve and to the source for stopping the motor and inducing a flow of pressure fluid through the compensating valve while the motor is stopped thereby operating the compensating valve to the throttling position while the motor is stopped and ready to immediately control the movement of the motor when the control valve is shifted from the stop position to either the third or fourth positions.
